FASTENING INSERTING MACHINE

Harold Ernest Elliott, Leicester, England, assignor to United Shoe Machinery Corporation, Borough of Flemington, N. J., a corporation of New Jersey

Application November 15, 1938, Serial No. 240,532.
In Great Britain January 4, 1938

14 Claims. (Cl. 1—41)

The present invention relates to fastening inserting machines and is illustrated herein as embodied in a machine of the general type disclosed in Letters Patent of the United States No. 5 786,190, granted March 28, 1905, on an application filed in the name of Louis A. Casgrain.

A machine of the type referred to is adapted to insert fastenings formed from short lengths of wire into work pieces such, for example, as top 10 lifts and heels to secure these parts together, this operation being commonly referred to as "slugging" the top lift to the heel. The machine is provided with a work support or horn which is spring pressed upwardly against a work plate 15 to clamp the work during the fastening inserting operation. As successive fastenings are inserted the horn is lowered a little to permit feeding of the work and, as the machine comes to rest, the horn is lowered a substantial distance against 20 its spring to permit removal of the work and the introduction of another work piece.

Heretofore machines of this type have been run at a speed of approximately 350 revolutions per minute inserting one fastening each revolution. At this speed trouble has arisen on account 25 of breakage and wear of parts and also from the fact that the clutch mechanism of the machine is operating near the limit of its capacity. These difficulties are seriously increased if it is attempted to run the machine at a higher rate of speed, for example, at a speed of 500 revolutions per minute.

An object of the present invention is to provide an improved machine of the type referred 30 to that will operate satisfactorily at a speed of 500 revolutions per minute.

To the attainment of this object and in accordance with one feature of the invention, there is provided in a fastening inserting machine of the type under consideration improved power 40 operated mechanism for lowering the horn from its work clamping position after the last fastening has been driven into the work and while the machine is coming to rest, this lowering action being started considerably earlier in the cycle 45 of the machine than heretofore, thereby providing more time for lowering the horn and putting less strain upon the means which actuates the horn lowering mechanism. As herein illustrated, the means for actuating the lowering mechanism 50 includes a cam and the portion of the rotation of this cam devoted to actuating the horn lowering mechanism has been substantially increased over previous constructions so that the lowering action has thus been made more gradual.

In accordance with another feature of the invention, the machine is provided with improved means for causing the return of the work support or horn to work clamping position substantially at the time the machine starts to operate, thereby insuring that the work will be clamped by the horn before the awl descends to pierce the work. As illustrated, the horn is freed from the control of the horn lowering mechanism by the release of a latch by which the horn is connected to its lowering mechanism while the machine is coming to a stop, and upon the release of said latch, a spring returns the horn immediately to work clamping position. The releasing of the horn, as herein illustrated, is effected by treadle 10 operated means at the same time that the clutch of the machine is rendered operative, the horn lowering mechanism itself being returned to its initial position gradually by the cam during a later portion of the machine cycle. 15

With the above and other objects and features in view, the invention will now be described in connection with the accompanying drawings and will thereafter be pointed out in the claims.

In the drawings:

Fig. 1 is a side elevation of a machine embodying the present invention;

Fig. 2 is an elevational view of parts of the machine as seen from the left-hand side of the machine;

Fig. 3 is a sectional view substantially along the line III—III of Fig. 1;

Fig. 4 is a view showing in front elevation and partly in section certain parts of the machine seen in Fig. 1; and

Fig. 5 is a side elevation of a clutch treadle of the machine.

The illustrated machine is provided with fastening inserting instrumentalities comprising an awl 7, awl actuating mechanism shown generally at 9, and adjustable by a knob 11, wire feeding and shearing mechanism (not shown), a driver 12, and a work support or horn H and actuating mechanism therefor, these parts being actuated by cams or similar means on a main 40 shaft 13 which extends from the front to the rear of the machine. On rotation of the main shaft 13 the following cycle is completed:

The awl 7 descends to pierce the work and, while in engagement with the work, moves to 50 the left, as viewed from the front of the machine, to feed the work. While the awl is moving to the left, the horn H which, during the greater part of the cycle is pressed upwardly by a spring 15 (Fig. 4) to clamp the work against a work 55

plate 17, is lowered about $\frac{7}{32}$ of an inch to release the work for feeding, this lowering being due to the operation of the horn actuating mechanism which will be described in more detail hereinafter. 5
5 As soon as the feeding of the work is completed, the horn H is allowed to rise under the action of the spring 15 and the awl rises out of the hole in the work and moves toward the right to its inoperative position. During movement of the 10 awl to the right the wire shearing mechanism, to which the wire feeding mechanism has now fed a predetermined length of wire for forming the fastener, operates to shear off the wire and transfer it into a position where it may readily 15 be driven into the hole pierced in the work. Finally the driver 12 descends to drive the fastener into the hole pierced by the awl.

The illustrated machine is also equipped with clutch and brake mechanism which is actuated 20 by a clutch treadle 16 (Fig. 5) under the control of the operator to bring the shaft 13, running at 500 revolutions per minute, to rest in a limited time and in a predetermined angular position, that is, a position whence the cycle just described 25 may be commenced. The nature of the clutch and brake mechanism will be described in more detail hereinafter.

To enable the operator readily to remove work from the machine when the clutch and brake 30 mechanism has brought the shaft 13 to rest, the illustrated machine is provided with horn drop mechanism, whereby, as the machine comes to rest, the horn H is depressed and caused to occupy an abnormally low position, that is, a position 35 lower than any which it occupies during the cycle of the machine so that there will be adequate clearance for removal of the work when the machine is at rest. The horn drop mechanism is so related to the clutch and brake mechanism that the horn H is only moved by the 40 horn drop mechanism into the abnormally low position when the clutch and brake mechanism is operative to stop the machine, the horn drop mechanism at other times being idle. Of the 45 parts above referred to, the awl actuating mechanism and driver actuating mechanism are preferably constructed and arranged in a manner similar to the corresponding mechanisms described in Letters Patent of the United States 50 No. 2,161,858, granted June 13, 1939, on an application filed in my name, while the wire shearing mechanism is preferably arranged in a manner generally similar to that of the corresponding mechanism described in United States Letters 55 Patent No. 2,052,659, granted September 1, 1936, on an application filed in the names of F. Ricks and H. E. Elliott. The wire feed may be effected in any convenient manner, for example, in the manner described in United States Letters 60 Patent No. 2,011,683, granted August 20, 1935, on an application filed in the names of H. Lane and G. W. Gibson.

The horn drop mechanism comprises a novel combination and arrangement of parts so devised that the mechanism operates satisfactorily even though the main shaft 13 is rotated at 500 revolutions per minute, these parts being to some degree interrelated with the mechanism for actuating the horn H during the cycle of the machine to release the work for feeding. The 65 mechanism is arranged and operated as follows:

The horn H, as shown in Fig. 1, comprises an 70 upstanding stem 19 at the top of which is mounted a rotatable button 21, the horn being provided at its lower end with a sleeve 23 which em-

braces a column or post 25 on which the horn is supported. The sleeve 23 is split vertically and may be secured in any desired position to the column 25 by a clamping handle 21 to accommodate work pieces of widely differing thicknesses. The column 25 is rectangular in cross section, and is slidably vertically in a supporting slide 29 which is itself arranged to slide in a guideway in the frame or column 33 of the machine, as shown in Fig. 4. 10

A pair of horn actuating toggle links 35, 37 (Fig. 4) are interposed between the horn column 25 and the supporting slide 29, the link 35 being pivotally connected at its upper end to the horn column 25 and the link 37 being pivotally connected at its lower end to the supporting slide 29. At the center of the toggle the adjacent ends of the links 35, 37 are pivotally connected to a third link 39, which extends horizontally to the right, as viewed from the front of the machine, 20 and is pivotally connected to an upstanding arm 41 mounted on a forwardly and rearwardly extending rock shaft 43. The shaft 43 has a second arm 45 secured to it which extends horizontally toward the right and is connected to a toggle actuating rod 47 which extends upwardly and is connected at its upper end to a bell crank lever 49 (Fig. 1), the lever 49 being operated by a cam 50. The supporting slide 29 is continually urged upwardly by the horn spring 15 and is 30 connected at its lower end by a rod 56 to the forward end of a balancing lever 52 (Fig. 5) mounted on a pivot 54 which extends laterally of the machine. The balancing lever 52 extends rearwardly of its pivot 54 and has connected to its 35 rearward end an upwardly extending rod 51 to the top of which is secured a rack plate 53, as shown in Fig. 2. The rack plate 53 is capable of vertical sliding movement in a guideway 55 forming a part of the column 33, and it has two rack 40 surfaces with teeth formed thereon, an upper rack 51 on its forward side and a lower rack 59 on its rearward side.

Mounted for engagement with the rack teeth 45 57, at certain times in the machine cycle, is a pawl 61 which co-operates with the rack surface to insure that the desired movements shall be imparted to the horn H by the toggle links 35, 37. The pawl 61 is pivotally mounted at its lower end at 63 upon a pawl carrying lever 65 which extends forwardly approximately horizontally from a transversely extending fixed pivot 67. At its forward end the lever 65 is pivotally connected at 69 to an upper link 71 of a pair of pawl actuating toggle links 71, 73. The link 71 55 extends downwardly and is pivoted to the lower link 13 which is formed by one arm of a bell crank lever 73, 75 which, in turn, is pivoted upon a transversely extending stud 77 secured to the column 33. The arm 75 of the bell crank lever 60 extends forwardly at right angles to the arm 73 and has connected thereto an upwardly extending pawl operating rod 79 coupled at its upper end to a cam operated bell crank lever (not shown). 65

The arrangement of the parts just described in connection with the actuation of the horn H is such that, when the main shaft 13 is running continuously and the horn drop mechanism is not in operation, the rod 47 is maintained in a raised position, as shown in Fig. 4, by the cam 50 to maintain the toggle links 35, 37 in a straightened condition during the greater part of the rotation of the shaft 13. During this period the rod 79 is maintained by its cam (not 75

- shown) in a lowered position, as shown in Fig. 2, so that the toggle links 71, 73 are in a position where the toggle is broken, and thus the forward end of the lever 65 is held in a lowered position.
- 5 When the forward end of the lever 65 is in this lowered position, a suitably shaped fixed stop 81, secured to the column 33, is operative to hold the pawl 61 out of engagement with the rack teeth 57 by contact with a lug 83 on the pawl. The 10 horn spring 15 may thus thrust the supporting slide 29 and the horn H upwardly to thrust the horn into clamping engagement with the work regardless, within limits, of the thickness of the work. When there is no work on the horn H, the 15 horn will occupy the position shown in Fig. 4 where further upward movement of the horn is prevented by contact of a stop 84 secured to the column 25 with the column 33.

Just before the commencement of the feed of the work by the awl 12, the rod 79 is elevated by its cam, thereby rocking the bell crank lever 73, 75 in a counterclockwise direction, as viewed in Fig. 2, straightening the toggle 71, 73, and lifting the forward end of the lever 65 so that the stop 81 no longer holds the pawl 61 out of engagement with the rack teeth 57. A spring pressed plunger 85, carried by the lever 65, then becomes operative to move the pawl 61 counterclockwise about its pivot 63 to cause it to engage the rack teeth 57. On engagement with the rack teeth 57 the pawl 61 prevents downward movement of the rack plate 53, and consequently prevents upward movement of the supporting slide 29 under the action of the horn spring 15. 30 During the feed of the work by the awl the rod 47 is moved downwardly by the cam 50 so that the toggle 35, 37 is broken towards the right and the horn H is lowered. As stated above, the machine is so arranged that the horn H is lowered about $\frac{3}{8}$ of an inch and it will be clear from the foregoing description that, since during the greater part of the machine cycle, the horn spring 15 is effective to thrust the horn up into clamping engagement with the work, variations in work thickness will make little or no difference to the amount of the lowering movement given to the horn H during the feed of the work by the awl. When, however, work presented to the machine differs greatly in thickness from that previously operated upon, for example, when high wooden heels suitable for women's shoes are presented to the machine following the operation upon low heels suitable for men's shoes, the operator will make a corresponding adjustment in the position 50 of the horn H upon the column 25 by means of the handle 27.

The horn drop mechanism will now be described. In the illustrated machine the horn H descends from its work clamping position to the abnormally low position mentioned above which is a distance of about $\frac{1}{8}$ of an inch below said work clamping position although this distance may be varied, as will be explained hereinafter, as the machine stops.

65 Mounted in the guideway 55 in the column 33 is a slide 87 (Fig. 2) carrying a pawl 89 which is arranged to engage the lower rack teeth 59 on the rack plate 53. The pawl 89 is mounted on the slide 87 for pivotal movement about an axis 70 extending widthwise of the machine and is urged in a clockwise direction, as viewed from the left-hand side of the machine, towards engagement with the rack teeth 59 by a spring pressed plunger 91 carried by the slide 87. When the machine is running continuously, the pawl 89 is

held out of engagement with the rack teeth 59 by a cam piece 93 fixed to the frame of the machine, the slide 87 being held in a lowered position against an adjustable stop 95 by a spring 97 (Fig. 2). The slide 87 has connected its upper end at 99 a connecting rod 101, shown in Figs. 2 and 3, the upper end of which is connected to the left-hand end of a rocking lever 103 (Fig. 3). The rocking lever 103 is pivoted freely upon a stud 105 which is located below and parallel to the main shaft 13 and is secured in the frame of the machine. The rocking lever 103 is provided with a slot 107 and the connecting rod 101 is pivoted to a stud 109 which passes through the slot 107 and may be adjusted along the slot, so that the amount of movement given to the slide 87 by rocking movement of the lever 103 may be varied, thereby varying the abnormally low position occupied at times by the horn H.

One cam 111 (Figs. 1 and 3) upon the cam shaft 13 constitutes a horn drop cam and cooperates with a roll 113 mounted at one end of a cam lever 115 freely pivoted on the stud 105 forwardly of the rocking lever 103. Adjacent to the roll 113 the lever 115 has pivotally connected thereto at 116 a depending double toothed pawl 117 having two depending teeth one above the other. The lower tooth 119 of the pawl 117 is adapted, at certain times, to engage a recess at the right-hand end of the rocking lever 103, as shown in Fig. 3, but while the machine is running continuously, the tooth 119 is held out of engagement with this recess, in a manner to be described hereinafter, and the cam lever 115 is oscillated idly by the cam 111, the double toothed pawl 117 moving up and down to the right of the recess. The roll 113 is held against the cam 111 by a spring pressed plunger 121 (Fig. 3) mounted in the machine frame.

The upper tooth 123 of the pawl 117 is adapted to engage a V-shaped groove in a controlling member 125. The controlling member 125 is pivotally mounted on a stud 127 which extends forwardly from a bell crank lever 129 having a lower arm 131 and being freely pivoted upon a pin 133 secured to the machine frame. The stud 127 is engaged in a slot 135 in the controlling member 125 and the controlling member has mounted therein a spring pressed plunger 137 which acts upon the stud 127 and normally urges the controlling member to the left, as viewed in Fig. 3, so that the stud 127 occupies a position at the right-hand end of the slot 135. Mounted in the bell crank lever 129 is a further spring pressed plunger 139 which acts upon the under side of the controlling member 125 and urges it upwardly in a clockwise direction about the stud 127 to hold the V-shaped groove therein against the upper tooth 123 of the pawl 117. The left-hand side of the V-shaped groove in the controlling member 125 is so arranged with regard to the upper tooth 123 that, when the lower tooth 119 is engaged in the recess in the rocking lever 103 and any appreciable stress is being transmitted from the cam 111 through the lever 115 and pawl 117 to the rocking lever 103 by the tooth 119, so that it becomes difficult to free the tooth 119 from its recess in the lever 103, rocking of the bell crank lever 129, 131 in a clockwise direction, to move the controlling member 125 to the right, from the position shown in Fig. 3, where the upper tooth 123 engages the V-shaped groove in the controlling member 125, causes the left-hand end of the controlling member 125 to dip, against the yielding action of the spring 75

pressed plunger 139 acting on its under side, so that the bottom of the V-shaped groove therein is no longer occupied by the tooth 123. If, however, the stress transmitted through the tooth 119 to the rocking lever 103 is reduced until it is inappreciable while the bell crank lever 129, 131 is rocked in the clockwise direction then the spring pressed plunger 139 will cause upward movement of the left-hand end of the controlling member 125 which, in turn, through the cam action of the left-hand side of the V-shaped groove upon the tooth 122, will draw the tooth 119 out of engagement with the recess in the rocking lever 103 until the tooth 123 occupies the bottom of the V-shaped groove.

10 The controlling member 125 is, as stated above, mounted upon a stud 127 secured to the upper arm of the bell-crank lever 129, 131 and the bell crank lever has a horizontally extending arm 131 to which is pivotally connected a downwardly extending rod 141. The lower end of the rod 141 is pivotally connected at 145 to a trip lever 143. The trip lever 143 extends widthwise of the machine and near its center is pivoted upon a 15 forwardly and rearwardly extending stud 147. The left-hand portion of the trip lever 143 comprises a flat tail 149. Beneath the tail 149 is arranged a vertical trip rod 151 which passes downwardly through a hole in a rearwardly extending bracket 153 on the frame of the machine. The trip rod 151 is urged downwardly by a spring 155 (Fig. 1) surrounding the rod and confined between a nut 157 threaded on the rod and the bracket 153. At its lower end the 20 trip rod 151 is pivotally connected to the rearward end of the clutch treadle 16 which is pivoted at 154 on the base of the machine and extends forwardly, bearing a tread plate 156 at its forward end. The arrangement is such that depression of the treadle 16 causes the trip rod 151 to rise against the action of the spring 155, to abut against the tail 149 of the trip lever 143, thereby rocking the trip lever in a clockwise direction, as viewed in Fig. 3, and thus causing the bell crank lever 129, 131, which carries the controlling piece 125, to rock in a clockwise direction to pull the controlling piece toward the right.

25 Freely mounted upon a pivot pin 159 (Figs. 1 and 3), which extends rearwardly from a bearing in the head of the machine and is supported in a bearing on the bracket 153, is a brake cam lever 163 carrying at its upper end a roll 165 (Fig. 3) which engages an enclosed track formed in the rear side of a brake cam 166 secured to the main shaft 13. Beneath its pivot pin 159 the cam lever 163 extends downwardly and has a lower portion 167 carrying an abutment 169 on its right-hand side. The abutment 169 is arranged at certain times to engage a spring pressed slide 171 carried by the trip lever 143, at which times, should the brake cam 166 cause counterclockwise rotation of the lever 163, the trip lever 143 will be urged bodily to the right. 30 Fixed to the pivot pin 159 and depending therefrom is a lever 173 and the stud 141, upon which the trip lever 143 is pivoted, is carried by the lever 173. The arrangement is such that when the trip lever 143 is pulled bodily to the right, the lever 173 is turned counterclockwise about the pivot pin 159. The pivot pin 159 has secured to its rearward end an arm 175 (Fig. 1) extending rearwardly and to the left. The arm 175 carries an upwardly extending V-block 177. 35 The V-block 177 co-operates with another V-

block 179 mounted upon the main shaft 13 in such a way that upward movement of the V-block 177 causes engagement of a friction clutch cone 161 rotatable with the main shaft 13 and a belt pulley 183 freely rotatable upon the shaft 13, so that the shaft 13 will be driven by the belt pulley 183. Downward movement of the V-block 177 allows the friction clutch to become disengaged.

40 Carried by the lever 173 is a safety handle 185, which is yieldingly retained in one or the other of two positions. In one of these positions the handle 185 extends downwardly substantially vertical and in the other position it extends to the right and substantially horizontal (as shown in Fig. 3), the two positions being separated by about 110°. The safety handle 185 is secured to a forwardly and rearwardly extending stub shaft 187 (Figs. 1 and 3) which at its forward end carries an eccentric pin 189. 45 The stub shaft 187 is mounted for rotation in a bore in the lever 173 and also for rotation in a bore in a lever 191 secured to the pivot pin 159 (see Fig. 1). Journaled upon the pin 189 is one end of a brake rim operating rod 193 the other end of which is connected at 195 to one end of an arcuate brake rim 197, which extends around the periphery of the brake cam 166 and is pivotally mounted upon the pivot pin 159 at its other end. In addition there is mounted upon the eccentric pin 189 a variable stop member 199 which is approximately Y shaped. The stem of the Y member carries a bearing which surrounds the eccentric pin 189 while the arms 201, 203 of the Y embrace a forwardly extending part of the 50 stud 147. The arm 201 of the Y at the left of the stud 147, as viewed in Fig. 3, carries an abutment surface 205 on its left-hand side.

55 The parts above described are arranged to co-operate in the following manner. When the safety handle 185 is in its horizontally extending position, as shown in Fig. 3, the eccentric pin 189 is approximately below the axis of the stub shaft 187, and thus the rod 193 occupies a position more to the right of that which it would 60 occupy were the pin 189 to the left of the axis of the stub shaft 187. Furthermore, the member 199 then occupies a position where the stud 147, which is below and to the right of the stub shaft 187, is closely adjacent to the junction of the arms 201, 203 so that the abutment surface 205 is nearer the axis of the stud 147 than it would be were the eccentric pin 189 to the left of the axis of the stub shaft 187. Considering the machine to be running continuously, the safety handle 185 as occupying its horizontally extending position, and the tread plate 156 of the treadle 16 as being held depressed, this position of the treadle will hold the trip rod 151 in an elevated position and the trip rod 151, by engaging the tail 149 of the trip lever 143, will hold that lever in a clockwise position, determined by a stop screw 206 which is arranged to engage the under side of the trip lever 143, this position being such that the spring pressed slide 171 is maintained below the path of the abutment 169 on the lower part 167 of the brake cam lever 163 and in a position where it cannot co-operate with the abutment. When the trip lever 143 is in this clockwise position, the bell crank lever 129, 131, which is connected to the trip lever 143 by the rod 141 will, as aforesaid, also occupy a clockwise position in which the controlling member 125 is moved to the right in Fig. 3 to hold the double toothed pawl 117 out of engagement with the rocking lever 103.

Under these conditions the brake cam 166 will oscillate the brake cam lever 163 idly and the horn drop cam 111 will oscillate the cam lever 115 idly. A spring 207 connected between the frame and part of the lever 173 will hold the lever 173 in a clockwise position and thus hold the clutch in engagement and the brake rim 197 away from the periphery of the brake cam by urging the rod 193 to the left, as viewed in Fig. 3. 5 The clockwise position taken by the lever 173 under the action of the spring 207 is limited by engagement of the abutment surface 205 on the member 193 with a fixed stop 209, and, since the distance between the abutment surface 205 and 10 the axis of the stud 147 is small (the safety lever 185 being in its substantially horizontal position), the lever 173 will occupy a position sufficiently clockwise to enable the clutch cone 181 (Fig. 1) to engage the pulley 183 sufficiently to drive the 15 machine, and to allow the brake rim 197 to be free of the periphery of the brake cam 166.

When it is desired to stop the machine, the clutch treadle 16 is released, allowing the trip rod 151 to descend under the action of its spring 25 155 so that the trip lever 143 may rock in a counterclockwise direction, under the action of a spring 211 connected thereto. The trip lever 143 being directly connected to the controlling member 125, does not, however, rock in a counterclockwise direction unless or until the horn drop cam 111 is so angularly oriented that the cam lever 115 actuated thereby is so disposed that the controlling member 125 may move to the left, as viewed in Fig. 3, to carry the double 30 toothed pawl 117 into position to engage the recess in the rocking lever 103, in other words, unless the right-hand end of the cam lever 115 is in an upper position where the pawl 117 is sufficiently high for the tooth 119 to pass over the right-hand end of the rocking lever 103 into position to engage the recess. The brake cam 166 and horn drop cam 111 are so arranged that, while the abutment 169 on the lower part 35 167 of the brake cam lever 163 is not in a left-hand position, the double toothed pawl 117 cannot be moved to the left as just described, the right-hand end of the cam lever 115 not being in an upper position. Consequently, when the clutch treadle 16 is released and the right-hand 40 end of the cam lever 115 is in, or reaches, an upper position which allows the trip lever 143 to swing in a counterclockwise direction to move the pawl 117 to the left, the abutment 169 on the brake cam lever 163 will then be at the left 45 55 end of the spring pressed slide 171, and upon further rotation of the main shaft 13 will be moved to the right to engage the left-hand side of the spring pressed slide 171, thereby rocking the lever 173 in a counterclockwise direction to free the friction clutch cone 181 from the belt pulley 183 and apply the brake rim 197 to the periphery of the brake cam 166. In this way should the machine tend to overrun the desired stopping position the brake cam 166 will continue to apply 60 65 the brake rim 197 to its own periphery with increasing force.

The continued rotation of the main shaft 13 which, inter alia, allows application of the brake rim 197 in the manner described above, also causes 70 the horn drop cam 111 to thrust down the cam lever 115, and since at this part of the machine cycle, the lower tooth 119 of the pawl 117 is in position to engage the recess in the rocking lever 103, such movement of the cam lever 115 75 will cause the rocking lever 103 to rock in a

clockwise direction to lift the slide 87 against the action of its spring 97.

Such lifting of the slide 87 will, with the clutch treadle 16 released, allow the pawl 89 carried thereon to ride off the cam piece 93 into engagement with the rack teeth 59 on the rack plate 53, thereby causing continued upward movement of the slide 87 to lower the horn the desired $\frac{1}{16}$ of an inch through the connection of the rack plate to the balancing lever 52 and through the connection of the latter to the supporting slide 29. The distance the horn is thus lowered may be raised by adjusting the stud 109 along the slot 187 at the left-hand end of the rocking lever 103. 10

As mentioned above, the stopping position of the machine is such that a cycle as described may be started therefrom, this cycle beginning with the piercing of the work by the awl. In order to hold the work upwardly against the thrust of the awl during the piercing operation, it is desirable to have the horn H in an elevated work clamping position at the time the awl starts to pierce the work. Furthermore, it is desirable to have the horn in work clamping position while the driver is driving the last fastening. The stopping position of the machine when the shaft 13 is run at 500 revolutions per minute has been arranged to be approximately 18° of rotation of the main shaft 13 before the piercing of the work by the awl and approximately 97° after the completion of the downward stroke of the driver. About 110° of rotation are allocated for that portion of the horn drop cam 111 which is operative to cause upward movement of the slide 87; of these 110° the 30 first 10° approximately are devoted to lifting the slide 87 sufficiently to enable the pawl 89 to ride off the cam piece 93 to engage the rack teeth 59, while the remaining 100° approximately are used in depressing the horn H against the action of the horn spring 15, the slide 87 and the rack plate 53 moving upwardly together. At the end of such downward movement of the horn H the machine comes to rest, so that the downward movement of the horn H commences just as the driver has completed its downward movement; the exact instant at which the horn H commences to lower under the action of the cam 111 in this manner varies a little, since the pawl 89 may just catch, or just miss, a tooth of the rack teeth 59 thereby 40 45 50 making the horn lowering a little early, or late, correspondingly.

On starting the machine, and before or as the awl starts to pierce the work, the horn H attains its work clamping position. In order that the horn H shall return to work clamping position before the awl starts to pierce the work, on starting the machine, the clutch treadle 16 is arranged to operate the pawl 89 in the following manner: (it being appreciated that when the 55 machine is at rest the pawl 89 is in engagement with the rack teeth 59 and itself is instrumental in connecting the slide 87 and the rack plate 53 so that the horn H is maintained in its abnormally low position). Connected to the rearward 60 end of the clutch treadle 16 is a vertically extending connecting rod 213 which is connected at its upper end to a rearwardly extending arm 215 of a pawl releasing lever 217. The lever 217 is pivoted about a fixed stud 219 extending laterally of the machine and has its arm 217 extending forwardly and downwardly to a point adjacent the pawl 89. The lower end of the arm 217 constitutes a tail 221 which, when the pawl 89 is in the elevated position it occupies in the stop position 65 70 75 80 85 90 95 98 100 105 110 115 120 125 130 135 140 145 tion of the machine, will, upon depressing the clutch treadle 16 swing rearwardly to disengage the pawl 89 from the rack teeth 59. When the pawl 89 has been disengaged in this manner a catch-pawl 223, from the forward end of which depends a tooth 225, immediately swings downwards about a pivot 227 on the slide 87 under the action of a spring 229 and the tooth 225 falls over the pawl 89 and prevents its reengagement with the rack teeth 59. When the machine is in the stop position and the pawl 89 is in engagement with the rack teeth 59 the tooth 225 of the catch-pawl 223 rests upon the top of the pawl 89, as shown in Fig. 2, and thus is prevented from swinging downwardly under the action of the spring 229. As soon as the pawl 89 has been released from the rack teeth 59 by actuation of the clutch treadle 16 in the manner described, the horn H moves rapidly upwardly under the action of the horn spring 15 and reaches its upper position within the 18° rotation of the main shaft 13 between the stop position and the piercing of the work by the awl, the rack plate 53 moving downwardly. The catch pawl 223 acts to hold the pawl 89 from falling back into engagement with the rack teeth 59 even though the treadle 16 be released immediately after depression and as the rack plate 53 moves downwardly.

In addition to actuation of the lever 215, 217, depression of the clutch treadle 16, when the safety handle 185 is in its substantially horizontal position, to raise the trip rod 151 causes the trip lever 143 to rock clockwise, so that the spring pressed slide 171 carried thereby is tripped out from engagement with the abutment 169 on the lower part 167 of the brake cam lever 163 so that the brake cam lever thereafter oscillates idly. The lever 173 may then swing under the action of the spring 207 in a clockwise direction to cause engagement of the clutch cone 181 with the belt pulley 183 to drive the machine and to cause the brake rim 197 to be freed from the periphery of the brake cam 166. Clockwise movement of the trip lever 143 will, as before described, rock the bell crank lever 129, 131 to pull the controlling member 125 to the right but, although the horn spring 15 is no longer acting to cause a thrust to be transmitted through the pawl 117, the spring 97 which, while the machine is running continuously acts to hold the slide 87 down against its stop 95, is sufficient to cause the double toothed pawl 117 to remain in engagement with the recess in the rocking lever 103, the upper tooth 123 of the pawl 117 leaving the bottom of the V-shaped groove in the controlling member 125 in the manner described hereinbefore. As the main shaft rotates, however, the horn drop cam 111 gradually allows the right-hand end of the cam lever 115 to rise, thereby lowering the slide 87. When this slide 87 touches its stop 95, the spring 97 is rendered idle, and the thrust transmitted through the double toothed pawl 117 is reduced sufficiently for the cam action of the V-shaped groove in the controlling member 125, acting on the upper tooth 123 of the pawl 117 to remove the lower tooth 119 of the pawl from the recess in the rocking lever 103, so that subsequent rotations of the horn drop cam 111 merely oscillate the cam lever 115 idly. In this way the horn drop cam 111 can be arranged to lower the slide 87 slowly. It is so arranged that 120° of rotation of the horn drop cam 111 are devoted to lowering the slide 87. Accordingly, the horn drop cam 111 is gently

inclined both on the part of the cam track which acts to lower the left-hand end of the rocking lever 103 and on the part of the track which acts to lift said lever. During lowering of the slide 87 the catch-pawl 223 acts in the manner described to maintain the pawl 89 out of engagement with the rack surface 59 until, as the slide 87 approaches its lowest position, the upper part of the cam piece 93 engages the lower side of the tooth 225 so that further downward movement of the slide 87 causes the catch-pawl 223 to be rocked against its spring 229 sufficiently to allow the tooth 225 to ride above the pawl 89 and onto the top thereof so that the pawl 89 may move into engagement with the cam piece 93. The cam piece 93 holds the pawl 89 out of engagement with the rack teeth 59, as aforementioned, when the machine is running continuously, the pawl 89 then being idle and not acting on the horn actuating parts, said pawl being brought into operation only when the clutch treadle 16 is released and the machine is being brought to its stopped position.

Should the clutch treadle 16 be depressed when the safety handle 185 occupies a more or less vertical position, then, although the trip lever 143 is thereby rocked in a clockwise direction sufficiently to free the spring pressed slide 171 carried thereby from the abutment 169 on the brake cam lever 163, the member 199 now is in such a position with regard to the stud 147 that, the abutment surface 205 on the arm 201 being relatively distant from the stud 147, the lever 173 is unable to rotate sufficiently far in a clockwise direction under the action of the spring 207 to allow the friction clutch to engage. Moreover, since the eccentric pin 189 on the stub shaft 187 of the safety handle 185 now occupies a position to the left of the axis of the stub shaft 187, what little clockwise movement of the lever 173 can execute under the action of the spring 207 will insure that the brake rim 197 is not in engagement with the periphery of the brake cam. When the safety handle 185 occupies its more or less vertical position, therefore, depression of the clutch treadle 16 does not cause the clutch to engage, but in every other respect the depression has effectively the same result as it has when the safety handle 185 is in its substantially horizontal position; the machine may thus be safely and readily turned over by hand when the safety handle 185 occupies its more or less vertical position.

While in the foregoing description the illustrated machine has been described as comprising a horn H, when it is desired that the machine should operate upon heels which are attached to shoes, the shoes being mounted upon lasts, the illustrated machine may be fitted with a suitable last supporting jack.

Having described my invention, what I claim as new and desire to secure by Letters Patent of the United States is:

1. In a fastening inserting machine, the combination of a work support, means tending constantly to elevate the work support into a work clamping position, power operated mechanism arranged to move the work support away from operative position while the machine is coming to rest and to maintain said support in this latter position while the machine remains at rest, a treadle for starting the operation of the machine, and means operated directly by said treadle as it starts the operation of the machine for causing said power operated mechanism to

- release its control of the work support and permit said elevating means to return the work support immediately to work clamping position.
2. In a fastening inserting machine, the combination of a work support, means tending constantly to elevate the work support into a work clamping position, mechanism arranged to lower the work support from work clamping position as the machine is coming to a stop and to maintain the support in this lowered position while the machine is at rest, a cam for actuating said mechanism, a treadle for starting the machine, and means arranged to be operated before the machine has started for releasing said lowering mechanism from the control of said cam substantially simultaneously with the starting of the machine, thereby permitting said elevating means to return the work support to work clamping position.
- 10 3. In a fastening inserting machine, the combination of a work support, means arranged to move the work support into work clamping position, mechanism including a pivoted latch for removing the work support a predetermined distance away from work clamping position as the machine is coming to rest and for holding said support in its removed position to permit the work to be taken from said support, a cam for operating said mechanism, a clutch, a treadle arranged to actuate said clutch, and means for releasing said latch to free the work support from the control of said cam simultaneously with the actuation of said clutch.
- 20 4. In a fastening inserting machine, the combination of a horn, means tending constantly to elevate the horn into a work clamping position, mechanism for lowering the horn when the machine comes to rest and for holding it in a lowered position, a latch for connecting the horn to said lowering mechanism, a treadle arranged to trip the machine, and means operated manually by depression of said treadle for releasing said latch and freeing the horn from said lowering mechanism as the machine is tripped, thereby permitting the horn to be raised by its elevating means into work clamping position substantially simultaneously with the actuation of the machine.
- 30 5. In a fastening inserting machine, the combination of a horn arranged during operation of the machine to be urged constantly into a work clamping position, mechanism for moving the horn away from work clamping position when the machine comes to rest and for holding it away from said position to permit the removal of the work, a clutch for operating the machine, a treadle for actuating said clutch, and means operated by said treadle prior to the actuation of said clutch for releasing the mechanism which holds the horn away from work clamping position as the clutch is actuated and thereby permitting said horn to be returned to said work clamping position substantially simultaneously with the starting of the machine by the actuation of said clutch.
- 40 6. In a fastening inserting machine, the combination of a horn, a spring tending constantly to elevate the horn into a work clamping position, mechanism including a latch arranged to lower the horn away from work clamping position as the machine comes to rest and to maintain the horn in its lowered position while the machine remains at rest, power operated means arranged to actuate said mechanism, a treadle for causing said power operated means to oper-
5. means for releasing said latch to free the horn from the control of said horn lowering mechanism and thereby permit said spring to return the horn to its work clamping position, and means including a pivoted member for preventing said horn lowering mechanism from acting upon the horn until the machine is again coming to rest.
- 10 7. In a fastening inserting machine, the combination of a horn, a spring tending constantly to elevate the horn into a work clamping position, a vertically movable member, connections between said member and said horn whereby elevation of said member lowers the horn away from work clamping position, mechanism for elevating said member and maintaining it in elevated position as the machine comes to rest, and means for releasing said member, thereby permitting said spring to elevate the horn again into work clamping position.
- 15 8. In a fastening inserting machine, the combination of a horn for supporting a work piece, a spring tending constantly to elevate the horn into a position to clamp the work piece, a vertically movable plate, connections between said plate and said horn whereby elevation of the plate will lower the horn away from work clamping position, power operated mechanism for elevating said plate and maintaining it in elevated position as the machine comes to rest thereby lowering said horn, and means for releasing said plate coincidently with the starting of the machine to permit said spring to elevate the horn into work clamping position substantially simultaneously with the starting of the machine.
- 20 9. In a fastening inserting machine, the combination of a horn, a spring tending constantly to elevate the horn into a work clamping position, a vertically movable member, connections between said member and the horn whereby elevation of said member lowers the horn and vice versa, a slide adjacent to said member and arranged for vertical sliding movement, means for connecting the slide to the vertically movable member, mechanism for elevating the slide and said member while so connected and thereby lowering the horn away from work clamping position, said mechanism acting also to maintain the slide in elevated position, and means arranged to disconnect said member from the slide and thereby permit the spring to lower said member and return the horn to its elevated work clamping position.
- 25 10. In a fastening inserting machine, the combination of a horn, a spring tending constantly to elevate the horn into a work clamping position, a vertically movable plate, connections between the plate and said horn whereby elevation of the plate lowers the horn, a slide adjacent to said plate and arranged for vertical sliding movement, a latch for connecting the slide and plate to each other, mechanism for elevating the slide and plate while so connected and while the machine is coming to rest, thereby lowering the horn away from work clamping position as the machine comes to rest, a treadle for starting the machine, means operated by said treadle for unlatching the slide and plate as the treadle is depressed to start the machine, and a member for holding said latch out of operative position until the machine is again coming to rest.
- 30 11. In a fastening inserting machine, the combination of a horn, a spring urging said horn into an elevated work clamping position, a vertically movable member, connections between said
- 35 40 45 50 55 60 65 70 75

member and said horn whereby elevation of the member lowers the horn and vice versa, mechanism for elevating said member a predetermined distance as the machine comes to rest, thereby 5 lowering the horn from work clamping position, said mechanism being constructed and arranged to maintain said member in its elevated position while the machine is at rest, power means for operating the machine, a treadle for rendering 10 said power means operative, and means operated by said treadle for releasing said vertically movable member from its elevated position and permitting said spring to return it to its lowered position and simultaneously to elevate the horn 15 into its work clamping position, thereby returning the horn to said work clamping position as said power means starts the operation of the machine.

12. In a fastening inserting machine, the combination of a horn, a spring tending constantly to raise the horn into a work clamping position, a vertically movable plate having rack teeth thereon, a pivoted lever connected at one side of its pivot to said horn and at the other side to 20 said plate so that movement of the plate in one direction moves the horn in an opposite direction and vice versa, a slide adjacent to said plate and movable vertically with respect thereto, a pawl carried by said slide and adapted to engage the 25 rack teeth on the plate, thereby connecting the slide and plate, power operated mechanism for elevating the slide as the machine comes to rest, thereby elevating the plate and lowering the horn away from work clamping position, said mechanism being arranged to maintain the slide in 30 said elevated position while the machine remains at rest, a clutch for operating the machine, a treadle arranged to operate said clutch, and means connected to said treadle for disconnecting the pawl from said rack teeth as the treadle 35 is depressed to actuate the clutch and thereby permitting the spring to return the horn to work clamping position as the machine starts, said means comprising a pivoted lever having an arm 40 arranged to engage said pawl and disengage it from said rack teeth, and a rod connecting said lever to the treadle.

13. In a fastening inserting machine, the combination of an awl for piercing the work to be 45 operated upon, a driver, a work supporting horn, 50

a spring tending constantly to elevate the horn into position to clamp the work while the awl and driver operate, means for depressing the horn from work clamping position to permit the work to be fed between successive fastenings, 5 mechanism for lowering the horn a predetermined distance from said work clamping position after the last fastening has been driven and while the machine is coming to rest and for maintaining said horn in said lowered position while the machine is at rest to permit removal of the work, power operated means for actuating the machine, a treadle for starting the operation of said power operated means, and means operated by 10 said treadle for releasing the horn from its lower- 15 ing mechanism as the machine starts to operate to permit the spring to return said horn to its elevated work clamping position simultaneously with the starting of the machine, thereby insuring that the work will be clamped before the awl 20 pierces the work.

14. In a fastening inserting machine, the combination of an awl for piercing the work to be operated upon, a driver, means for actuating the awl and driver, a work supporting horn, a spring 25 tending constantly to elevate the horn into position to clamp the work, a main shaft, power means for rotating said shaft, a cam on said shaft, mechanism actuated by said cam for lowering the horn away from work clamping position 30 against the action of said spring after the final fastening has been driven and while the machine is coming to rest, said cam utilizing approximately one-third of its rotation in actuating said 35 lowering mechanism and being arranged to maintain said mechanism in its actuated position while the machine is at rest, a treadle for initiating the operation of said power means to rotate said main shaft, and means operated by said treadle for releasing the horn from the control of said 40 lowering mechanism and permitting said spring to return the horn to its elevated work clamping position substantially as the main shaft starts to rotate, thereby insuring that the work will be clamped before the awl starts to pierce the work 45 while also permitting said cam to return the horn lowering mechanism gradually to its initial position and thereby reduce strain on the cam.

HAROLD ERNEST ELLIOTT. 50
